UNITED STATES PATENT OFFICE.

JOSEPH BETHENOD, OF PARIS, FRANCE.

RADIOTELEGRAPHIC COUPLING.

Original application filed September 2, 1919, Serial No. 321,259. Divided and this application filed February 16, 1922. Serial No. 536,927.

To all whom it may concern:

Be it known that I, JOSEPH BETHENOD, a citizen of the French Republic, residing at Paris, France, have invented certain new and useful Improvements in Radiotelegraphic Couplings (for which I have filed applications in France March 15 and July 30, 1918), of which the following is a specification.

10 This invention relates to an improved system of coupling between an antenna (radiotelegraphic) and a high frequency alternating current generator of the type of those susceptible to furnishing directly a current 15 of the frequency necessary for the feeding of the antenna. The invention is a modification of the invention set forth in my co-pending application Serial No. 321,259, filed September 2, 1919, in which the windings of 20 the alternator are divided into sections.

In the present invention, as illustrated on the drawing, the armature windings are divided up into a number of parts C_1 , C_2 , C_3 and all these partial windings of the alternator and all the primary windings of the transformers T_1 , T_2 , T_3 are coupled in series in a single circuit to cause the partial windings of the alternator and the primary windings of the transformers to alternate in the 30 order of this coupling, the secondaries of the said transformers being coupled up in series for example and the whole being connected between the antenna A and the earth E.

The tension created in one fraction or section of the generator winding (such as C_1) is balanced by the voltage loss in the primary winding of the corresponding transformer (such as T_1); the maximum tension to which

the insulators of the generator are subjected is therefore found to be the same as if the fractions of the winding were electrically independent.

I claim as my invention:

1. A radiotelegraphic station, comprising in combination a high frequency alternator 45 in which the armature winding is divided into several sections not comprising any direct electric connection between them, and a complex of transformers magnetically independent of each other, the number of 50 transformers being equal to that of the said sections of the armature, the primary windings of the transformers being inserted in series in a circuit, alternately with the sections of the armature, and the secondary 55 windings of these transformers being connected to the transmitting antenna in a suitable manner.

2. A radiotelegraphic station comprising in combination a high frequency alternator 60 in which the armature winding is divided into a plurality of sections having no direct electrical connection with each other, and a complex of transformers magnetically independent of each other, the number of 65 transformers being equal to the number of the said sections, and the primary windings of the transformers being inserted in series in a circuit and alternating with the said sections whilst the secondary windings of the 70 transformers are coupled up in series and are all connected up between the antenna and the earth.

In testimony whereof I have hereunto affixed my signature.

JOSEPH BETHENOD.
